(57) **CLAIM**

The ornamental design for a cooler box, as shown and described.

DESCRIPTION

FIG. 1 is a front elevational view of a cooler box as shown and described;

FIG. 2 is a left side elevational view, the right side being identical thereto;

FIG. 3 is a front, right, top perspective view thereof;

FIG. 4 is a top plan view thereof; and,

FIG. 5 is a bottom plan view thereof.

The broken lines and the areas within them depict portions of the cooler box that form no part of the claimed design.
